CHRISTMAS ORNAMENT

Dario Moranduzzo, Via Aretina 161, Florence, Italy

Filed May 9, 1967, Ser. No. 7,030

Term of patent 14 years

(Cl. D29—1)

FIGURE 1 is an elevational view of a Christmas ornament, showing my new design,

FIGURE 2 is a sectional view taken on line 2—2 of FIGURE 1,

FIGURE 3 is a sectional view taken on line 3—3 of FIGURE 1,

FIGURE 4 is a sectional view taken on line 4—4 of FIGURE 1,

FIGURE 5 is a sectional view taken on line 5—5 of FIGURE 1,

FIGURE 6 is a sectional view taken on line 6—6 of FIGURE 1, and

FIGURE 7 is an enlarged fragmentary view of the edging which extends around each of the jewels.

The dot-dash lines in FIGURE 1 denote that the same surface ornamentation and rays as shown in solid lines continue around the ornament.

I claim:

The ornamental design for a Christmas ornament, as shown and described.
